UNITED STATES PATENT OFFICE

162,951

PIN CUSHION OR SIMILAR ARTICLE

Ruth Haon, New York, N. Y.

Application November 9, 1950, Serial No. 12,921

Term of patent 14 years

(Cl. D3—19)

To all whom it may concern:

Be it known that I, Ruth Haon, a citizen of the United States of America, residing in New York city, county of New York, and State of New York, have invented a new, original, and ornamental Design for a Pin Cushion or Similar Article, of which the following is a specification, reference being had to the accompanying drawing, forming part thereof, wherein,

Figure 1 is a side elevational view of a pin cushion or similar article showing my new design.

The wavy lines on the head, back and feet sections represent fabric texture.

I claim:

The ornamental design for a pin cushion or similar article, substantially as shown and described.

RUTH HAON.
